UNITED STATES PATENT OFFICE.

CARL A. OLSON, OF MILAN, MINNESOTA.

HOISTING APPARATUS.

No. 867,071.

Specification of Letters Patent.

Patented Sept. 24, 1907.

Application filed March 28, 1907. Serial No. 365,037.

To all whom it may concern:

Be it known that I, CARL A. OLSON, a citizen of the United States, residing at Milan, in the county of Chippewa and State of Minnesota, have invented certain new and useful Improvements in Hoisting Apparatuses; and I do declare the following to be a full, clear, and exact description of the invention, such as will enable others skilled in the art to which it appertains to make and use the same.

10 This invention relates to improvements in hoisting apparatus.

The object of the invention is to provide an apparatus of this character by means of which the hoisting rope or cable will be automatically locked, upon release of the 15 hoisting power, by means of the weight of the load being hoisted.

A further object is to provide means whereby the locking mechanism for the hoisting cable may be quickly released.

20 With the foregoing and other objects in view which will appear as the nature of the invention is better understood, the invention consists in certain novel features of construction, combination and arrangement of parts as will be hereinafter described and claimed.

25 In the accompanying drawings, Figure 1 is a side view of the hoisting apparatus constructed in accordance with the invention; Fig. 2 is an edge view of the same; Fig. 3 is a longitudinal vertical sectional view through the main pulley frame and the cable locking mechanism carried thereby.

30 Referring more particularly to the drawings, 1 denotes the main pulley frame which is here shown and preferably consists of a series of parallel plates 2 which are spaced apart and secured in position by means of bolts or rivets 3 which also serve as pivot bolts for the working parts of the block. Connected to the upper pivot bolts 3 between the inner pair and the two outer plates of the frame is secured a bail 4 to which is connected a hook 5 by means of which the main frame 1 may be suspended from and connected to a suitable support.

35 Pivotaly mounted on the central pivot bolt 3 between the inner pair of plates 2 is an auxiliary pulley frame 6 which consists of a pair of horizontally-extending plates between which near the upper edge and adjacent to one end thereof is revolubly mounted a pulley 7 while between the same and adjacent to the opposite end and near the lower edge thereof is revolubly mounted a pulley 8. The plates of the frames 6 are secured 40 together at their opposite ends by rivets 9 and are spaced apart by means of sleeves 10 arranged on said rivets.

45 To the lower rivet at one end of the frame 6 is connected a pulley block 12, said pulley block being 50 loosely connected to the rivet by means of a bail 13. On the lowermost bolt 3 of the main frame 1 between

the inner pair and the two outer plates thereof are revolubly mounted pulleys 14.

55 Adapted to be used in connection with the main pulley frame and pulleys is a triple pulley block 15 which is here shown and preferably consists of a series of plates which are secured together by rivets or bolts 16 on which are arranged sleeves 17 whereby said plates are spaced apart and held in parallel relation. Revolubly mounted on a central pivot bolt 18 between the inner 60 pair of plates on the two outer plates are three pulleys 19. To the bolt 16 in the lower end of the pulley frame 15 is secured bails 20 to which is connected a hook 21 which is adapted to be connected to the load to be raised or hoisted. To the bolt or rivet 16 at the upper 70 end of the frame is secured a bail 22.

75 To the bail 22 is connected the lower end of the hoisting cable 23, said cable passing upwardly from the bail 22 around one of the pulleys 14, the lower end of the main frame and from thence passes downwardly around one of the pulleys 19 in the frame 15, thence upwardly through the pulley block 12, thence downwardly around another of the pulleys 19 and the frame 15 and upwardly around the other pulley 14 in the lower end of the main frame 1 and thence downwardly around the 80 central pulley 19 of the frame 15 after which the cable passes upwardly over the pulleys 7 and 8 in the auxiliary pulley frame 6 and from thence extends to and is connected with the operating power. By running the hoisting cable as herein shown and described, the pivoted auxiliary frame 6 will be held thereby in a horizontal position when the load is applied to the hook 21 of the pulley frame 13 and the power is applied to the opposite end of the hoisting cable.

90 In order that the load may be suspended in position at any desired elevation or to prevent the same from dropping should the hoisting cable be broken, I provide a suitable locking mechanism whereby said cable will be automatically gripped and held should the same be broken between the hoisting mechanism and the main pulley frame. The locking mechanism for the cable is here shown and preferably consists of a clutching or gripping lever 24 which is pivotally mounted at one end on the bolt or rivet 9 at one end of the auxiliary pulley frame 6 and projects above and over said frame as shown. The lever 24 is provided with an obliquely-disposed or cam slot 25 which is adapted to be engaged with the upper pivot bolt 3 of the main frame 1 between the inner pair of the plates forming said frame. The outer or free end of the lever 24 is bent downwardly and outwardly to form a cable gripping plate 26 which is adapted to be brought into tight engagement with the cable 23 immediately above the pulley 7 of the auxiliary frame 6 thereby clamping said cable between the pulley and said gripping plate 100 105 and holding the same against backward movement. The gripping plate 26 is automatically brought into 110

engagement with the hoisting cable by means of the slotted connection between said lever and the bolt 3 of the main frame and the connection of the auxiliary pulley frame which when the hoisting power is released will be tilted or swung in the frame 1 by the weight of the load pulling downwardly upon the pulley block 12 at one end of the frame 6 thereby drawing said end downwardly and raising the opposite end of the frame together with the cable which passes over the pulley 7 at this end of the frame. The tilting or swinging movement of the auxiliary frame 6 also tends to force the gripping plate 26 of the lever 24 downwardly by reason of the slotted engagement of said lever with the main frame so that the hoisting cable is tightly gripped or clamped between the pulley 7 and the gripping plate of the clutch lever, as will be understood.

In order to disengage the gripping lever from the cable to permit the further hoisting of the load, I provide a suitable releasing mechanism which consists of a lever 27 which is pivotally mounted on the central pivot bolt 3 of the main frame 1 between the inner pair of plates and the outer plate on one side of said frame. The inner end of the lever 27 is loosely connected to one end of a bell-crank lever 28 which is pivotally mounted on the adjacent side of the auxiliary pulley frame 6 near one end of the same. The opposite end or arm of the bell-crank lever 28 is pivotally connected to the upper end with a fulcrum arm 30 or bar 29, the opposite end of which is pivotally connected to the lower pivot bolt 3 of the main frame. To the free or outer end of the releasing lever 27 is connected a releasing rope or cord 30 which extends downwardly to within convenient reach of the operator and is adapted when drawn upon to rock the releasing lever 27 downwardly which will cause the opposite or upper end of said lever to rock the bell-crank lever which movement owing to the pivotal connection of the opposite arm of the bell-crank lever with the fulcrum arm or bar 29, the opposite end of the auxiliary pulley frame 6 to be tilted upwardly, this movement will lift or swing the clutching lever 24 upwardly, thereby disengaging the gripping plate 26 from the cable. This separation or disengagement of the gripping plate 26 from the cable is also facilitated by the downward or opposite movement of this end of the auxiliary pulley frame 6.

From the foregoing description taken in connection with the accompanying drawings, the construction and operation of the invention will be readily understood without requiring a more extended explanation.

Various changes in the form, proportion and the minor details of construction may be resorted to without departing from the principle or sacrificing any of the advantages of the invention, as defined by the appended claims.

Having thus described my invention, what I claim as new and desire to secure by Letters-Patent is,—

1. A hoisting apparatus comprising a main pulley frame, 60 an auxiliary pulley frame pivotally mounted in said main

frame, pulleys arranged in said main frame and in said auxiliary frame, a pulley block loosely connected to one end of said auxiliary frame, a triple pulley block, a hoisting cable having one end connected to said triple block and passing around the pulleys therein and the pulleys in said main and auxiliary frames, gripping means adapted to engage the hoisting cable when the hoisting power is released therefrom, and means for disengaging said gripping means from said cable.

2. A hoisting apparatus consisting of a main pulley frame, pulley wheels journaled in the lower end of said frame, and auxiliary pulley frame pivotally mounted in said main frame, pulley wheels revolvably mounted in the opposite ends of said auxiliary frame, a pulley block loosely connected to one end of the latter, a triple pulley block, a hoisting cable connected at one end to said triple block and passing around the pulleys therein and pulleys in said main and auxiliary frames, a gripping or clutching lever pivotally mounted in one end of said auxiliary frame and adapted to be engaged thereby with the hoisting cable when the hoisting power is released therefrom, and means to disengage said gripping or clutching lever from said cable, substantially as described.

3. A hoisting apparatus comprising a main pulley frame, pulley wheels journaled in the lower end thereof, an auxiliary pulley frame pivotally mounted in said main frame, pulley wheels journaled in the opposite ends of said auxiliary frame, a pulley block loosely connected to one end of the latter, a triple pulley block, a hoisting cable connected at one end to said block and passing around the pulleys therein and pulley wheels in said main and auxiliary frames, a clutch or gripping lever pivotally mounted in one end of said auxiliary frame, said lever having formed therein a cam slot to engage a fixed pin or bolt in said main frame whereby upon the release of the hoisting power from said cable said auxiliary frame will be tilted by the weight of the load to cause said clutching or gripping lever to engage and clamp said hoisting cable between the free end of said lever and the pulley in the adjacent end of said auxiliary frame, and means to release 100 said clutch lever, substantially as described.

4. A hoisting apparatus comprising a main pulley frame, pulley wheels journaled in the lower end thereof, an auxiliary pulley frame pivotally mounted in said main frame, pulley wheels journaled in the opposite ends of said auxiliary frame, a pulley block loosely connected to one end of the latter, a triple pulley block, a hoisting cable connected at one end to said block and passing around the pulleys therein and pulley wheels in said main and auxiliary frames, a clutch or gripping lever pivotally mounted in one end of said auxiliary frame, said lever having formed therein a cam slot to engage a fixed pin or bolt in said main frame whereby upon the release of the hoisting power from said cable said auxiliary frame will be tilted by the weight of the load to cause said clutching or gripping lever to engage and clamp said hoisting cable between the free end of said lever and the pulley in the adjacent end of said auxiliary frame, a fulcrum arm on said main frame, a bell-crank lever pivotally mounted on the adjacent end of said auxiliary pulley frame, one arm of said bell-crank lever being pivotally connected to said fulcrum arm, a releasing lever pivotally mounted on said main frame and loosely engaged with the opposite arm of said bell-crank lever whereby when said releasing lever is actuated, said bell-crank lever will tilt or rock said auxiliary pulley frame and thereby disengage said fulcrum lever from said hoisting cable and an operating cord connected to said releasing lever, substantially as described.

In testimony whereof I have hereunto set my hand in presence of two subscribing witnesses.

CARL A. OLSON.
